(57) **CLAIM**

The ornamental design for a mount for mobile electronic devices as shown and described.

DESCRIPTION

FIG. 1 is a front perspective view of a mount for mobile electronic devices in accordance with a first embodiment of my new design;

FIG. 2 is a rear perspective of the mount of FIG. 1;

FIG. 3 is a front elevation view of the mount of FIG. 1;

FIG. 4 is a rear elevation view of the mount of FIG. 1;

FIG. 5 is a right side elevation view of the mount of FIG. 1;

FIG. 6 is a left side elevation view of the mount of FIG. 1;

FIG. 7 is a top plan view of the mount of FIG. 1;

FIG. 8 is a bottom plan view of the mount of FIG. 1;

FIG. 9 is a front perspective view of a mount for mobile electronic devices in accordance with a second embodiment of my new design;

FIG. 10 is a rear perspective of the mount of FIG. 9;

FIG. 11 is a front elevation view of the mount of FIG. 9;

FIG. 12 is a rear elevation view of the mount of FIG. 9;

FIG. 13 is a right side elevation view of the mount of FIG. 9;

FIG. 14 is a left side elevation view of the mount of FIG. 9;

FIG. 15 is a top plan view of the mount of FIG. 9; and,

FIG. 16 is a bottom plan view of the mount of FIG. 9.

The broken lines depict portions of the mount for mobile electronic devices that form no part of the claimed design.

1 Claim, 16 Drawing Sheets
